PEN NIB AND METHOD OF MAKING SAME

John A. Shea, Jersey City, N. J.

Application February 28, 1940, Serial No. 321,217

2 Claims. (Cl. 113—32)

This invention relates to the manufacture of a completed pen nib from a strip of metal, and contemplates an intermediate step therein, the object of which is to smooth the corners and edges of the writing tip and at the same time hardening the tip by compressing the corners and edges of the same.

In my co-pending applications, Serial No. 211,823, filed June 4, 1938, now Patent No. 2,195,430, issued April 2, 1940, and Serial No. 238,552, filed November 3, 1938, now Patent No. 2,208,477, issued July 16, 1940, there is shown a pen and a method of making pen nibs from a continuous strip of metal, and the present invention is directed toward the step of smoothing and hardening the corners and edges of the writing tip.

Instead of tumbling individual pens, which is and has been the manner of smoothing metal pens preferably of stainless steel up to the present time, I have reduced this to a precise mechanical operation by a pressure of upper and lower dies on the edges and corners of the writing tip that not only smooths these edges and corners, but simultaneously hardens the metal by the vise like pressure applied by these dies.

In my co-pending application, Serial No. 238,552, filed November 3, 1938, there is shown a method of making pens from a continuous strip of metal, and this method of smoothing pens is one of the operations made possible by that strip method.

It will be readily seen that by this smoothing operation, I am enabled to complete the pen in final shape for writing, whereas heretofore the necessary tumbling operation on the individual blanks was one of the reasons why it has been impossible to manufacture a pen in one continuous operation.

The invention will be more fully described hereinafter, embodiments will be shown in the drawing, and the invention will be finally pointed out in the claims.

In the accompanying drawing:

Figure 1 is a plan view of a pen tip forming a part of the nib of the pen, showing the same in final rounded or smoothed condition;

Figure 2 is a partial plan view of the body strip which is cut out to form the nib of the pen from tip to shoulder, the remaining part of the strip body being unoperated upon;

Figure 3 is a plan view of the tip of the nib as it is formed by the first cutting out operation of the cutting out dies;

Figure 4 is a transverse section taken on line 4—4 of Figure 3;

Figure 5 is a transverse section of the same blank shown in Figure 4, showing it so-related to the rounding or smoothing dies;

Figure 6 is a transverse section of the blank after the rounding action of the dies shown in Figure 5 has been completed;

Figure 7 is a partial transverse section showing the action of the forces upon the material forming the blank during the operation of the dies, and it is a partial section taken on line 7—7 of Figure 1;

Figure 8 is a similar section but modified by the use of dies of different curvatures;

Figure 9 is a plan view of a completed pen tip having wings such as shown in Figure 1, but having between the wings a slot which separates the two wings; this plan view shows the pen tip in completed form with the corners and edges rounded; and

Figs. 10 and 11 are partial transverse sections of a blank similar to Figure 8 but made with dies of a still different curvature, whereby a certain pointed portion results—these views resulting also form a swaging section of the dies.

Similar characters of reference indicate corresponding parts throughout the various views.

Referring to the drawing, and more particularly to Figure 2, the strip body 10 is provided with a die registration hole 11 and a pierce hole 12 and a nib 13 having wings 14 and 15 thereon. The strip 10 is subjected to a cutting action whereby the V-shaped space 16 is cut out and by successive operations of this die, cutting out this V, the nib portion 13 which extends from the strip 10, remains. One form of the wings 14 and 15 is shown in Figure 3 and another form of wings 14a and 15a is shown as part of the nib 13a in Figure 9, having a slot 17 between the wings. When these wings, either of Figures 3 or 9, have been cut out by the die operation that removes the material 16, the metal has relatively sharp corners and edges 20, 21, 22 and 23, as shown in Figure 4.

The invention consists in subjecting this metal with such corners and edges 20, 21, 22 and 23 to a rounding operation so as to shape the cross section shown in Figure 4 into the cross section shown in Figure 6 where the corners and edges 20a, 21a, 22a and 23a are rounded. This rounding action takes place by subjecting the wings to the operation of a die consisting of an upper part 25 and a lower part 26 suitably operated in the manner well known.

The opposite faces of each of these dies have a shall recess 27 for the upper die and a similar shallow recess 28 for the lower die, having filleted corners 30. When these dies 25 and 26 are pressed together, the more or less right angle corners and edges of the blank or nib 13 therebetween are subjected to pressure as indicated by the arrows 32 in Figure 7, and this diagonal inward pressure causes a slight outward pressure as shown by the arrow 33 in Figure 7 which brings about a gentle rounding action along the sides of the blank or nib 13. It will be noted that the curved portions or fillets 30 of both of the dies 25 and 26 extend slightly beyond the length of the blank or nib 13 therebetween. The length of the blank is shown by the double headed arrow marked X, and the length of the recesses is shown by the doubled headed arrow marked Y, in Figure 5.

It will also be noted that when the blank or nib 13 is about to be engaged by the pressure action of the dies, the lower corners of the blank or nib 13 rest against the fillets 30 about as shown in Figure 5. A similar relation between the corners of the blank and the fillets 30 of the upper die 25 is brought about when the upper die 25 is lowered so as to be in contact with the blank or nib 13. The continued action of the dies toward each other brings about the pressure action as shown in Figure 7. In a modified form, the pressure action upon the corners may be increased by changing the curvature of the fillets 30 so as to bring about a general rounded side as shown in Figure 8, the parts between the arrows 35 being more or less straight, although theoretically it is slightly rounded by the pressure action indicated by the arrow 33 in Figure 7. In other words, one pressure action result of the dies is shown in Figure 7. A more compact pressure action result is shown in Figure 8. A still more compact pressure action result is shown in Figure 10.

The dies 25 and 26 are so shaped as to conform either to the contour shown in Figure 3, whereby a rounding action is brought about as shown in Figure 1, or the die may be shaped to conform to the general contour of the embodiment shown in Figure 9, whereby the rounding action takes place all around the sets of each wing, and in Figure 9 from about the point 37 to the point 38 of one wing 14a and from the point 39 to about the point 40 of the other wing 15a.

In the embodiment shown in Figure 1, the rounding action is continuous from about the point 42 to about the point 43 of the form shown in Figure 1.

The pressure applied to the dies in the description just made is mainly for the purpose of smoothing the corners and edges, and at the same time compressing the metal along the contours indicated, thereby strengthening and hardening the metal. The operation of the dies can be carried out with still greater pressure so as to bring about a swaging action and result in a tightly compressed metal substantially through-

out the cross section area of the nib, with the edges particularly hard. The important feature is a condensation of the metal along the contour between 42 and 43 in Figure 1, or between 37 and 38, and 39 and 40, in Figure 9, because it is this contour that is used as a writing edge, and it is particularly desirous to have this very smooth and also hard.

On the other hand, such swaging action in the sense that the dies act upon the entire lateral sides up to the point where the faces of the die meet will bring about a more pointed contour, the object of which is to provide a finer writing nib, as shown in Figure 10 by the character 44. This swaging action thus compresses the metal throughout, and from its contour inwardly will harden the metal and with the portion 44 will provide a very hard surface for the writing portion of the nib.

Reference is made to co-pending applications Ser. No. 325,105, filed Mar. 21, 1940, and Ser. No. 321,218, filed Feb. 28, 1940, respectively, to issue on the same date herewith, and the pending application, Ser. No. 357,926, filed Sept. 23, 1940.

I have described the invention in connection with the embodiment shown, but it is clear that changes may be made therein without departing from the spirit of the invention as set forth in the appended claims.

What is claimed is:

1. In the method of manufacturing finished winged pens from a blank strip of metal having laterally extending wings in the plane of the nib, the step which consists in subjecting the contour corners and edges of the wings along their entire contour of each of the pen nibs while the wings are in the plane of the nib, to the action of equal compression forces around the entire contour only, the body of the metal within the contours remaining without deformation, to equally smooth, round and harden said contour only, the intensity of compression of the metal along the entire contour being determinative of the character of the writing tip of each of the pen nibs when the wings are bent to writing position for the writing of fine, medium or coarse lines.

2. A pen nib blank laterally extended from a continuous strip of metal along one side thereof, said pen nib blank having circular shaped wing portions in the plane of the nib on opposite sides of the median plane thereof adapted when bent from the plane of the nib to form a writing tip with writing surfaces along the circular surfaces of greater distance from said median line, the contour corners and edges of said wing portions only being smooth, round and hard and having the same shape throughout the contour, the metal along the entire contour of said wing portions being compressed equally along said contour, the body of the metal enclosed by said compressed contour being undeformed, the wings being in the plane of the nib.

JOHN A. SHEA.
